Primary Examiner — Katrina A Betton*(74) Attorney, Agent, or Firm* — Dickinson Wright PLLC(57) **CLAIM**

The ornamental design for a tire, as shown and described.

DESCRIPTION

FIG. 1 is a perspective view of the tire of our design; FIG. 2 is a front elevation view of the tire of our design; FIG. 3 is a rear elevation view of the tire of our design; FIG. 4 is a side elevation view of the tire of our design; FIG. 5 is a side elevation view of the tire of our design, taken from the opposite side of that shown in FIG. 4; and, FIG. 6 is an enlarged, partial view of the tire of our design, taken from FIG. 1.

The dash-dot-dot-dash lines between the shoulder and sidewall define the boundaries of the claim. The broken line disclosure in the drawings depicts environmental subject matter forming no part of the claimed design. The tread pattern repeats over the circumferential surface of the tread.
